UNITED STATES PATENT OFFICE.

GEORGE E. ULRICH, OF BUFFALO, NEW YORK, ASSIGNOR TO EASTMAN MACHINE COMPANY, OF BUFFALO, NEW YORK.

KNIFE FOR CLOTH-CUTTING MACHINES OR THE LIKE.

Application filed May 28, 1924. Serial No. 716,367.

To all whom it may concern:

Be it known that I, GEORGE E. ULRICH, a citizen of the United States, residing at Buffalo, in the county of Erie and State of New York, have invented a new and useful Improvement in Knives for Cloth-Cutting Machines or the like, of which the following is a specification.

This invention relates to improvements in knives for cloth cutting machines, more particularly to knives of the sort used with reciprocating cloth cutting machines.

In machines of this kind a straight, thin, elongated knife or blade is provided which is secured at one end to a slide or other means for imparting reciprocating motion thereto. The knife is arranged to reciprocate or slide in a substantially upright guide slot formed in a standard or leg, on the upper end of which a motor and the necessary driving connections are mounted, while the lower end of the standard is secured to a throat plate attached to the usual base plate which moves beneath the cloth or other material being cut. The throat plate is provided with the usual longitudinal throat or opening extending therethrough and which forms substantially a continuation or enlargement of the guide slot, and the knife moves towards and from the throat when cutting the material.

Heretofore, in machines of this type, the knife has been formed with a straight, continuous square or flat heel portion or back edge, and the opposite sides of the knife extend parallel or substantially parallel to each other, and the guide slot is of similar shape and fits closely against the back of the knife and a portion of each side, so as to leave the cutting edge exposed or extending out of the guide slot. The back of the knife therefore engages with the back of the guide slot for the full length of the knife, in its movements up and down therein.

In practice, this formation of the knife and resulting continuous contact with the back of the guide slot, is objectionable for the reason that small particles of lint or the like, from the material being cut, enter the lower end of the guide slot from the throat and from the space above and adjacent thereto during the upward strokes of the knife, with the result that the lint and the lubricant supplied to the knife in the slot

form a gummy deposit which clogs the guide slot and impedes the free action of the knife to such an extent that the proper working of the machine is impossible without frequent cleaning of the knife and guide slot.

The principal object of the present invention is to provide a cutting knife or blade for reciprocating cloth cutting machines which is formed and adapted, in its reciprocating movements, to keep the slot free of accumulations or deposits and thereby overcome the difficulties heretofore encountered.

Another object is to improve the construction of cloth cutting knives in the other respects hereinafter specified and claimed.

In the accompanying drawings:

Fig. 1 is a fragmentary side elevation of a cloth cutting machine of the reciprocating type, provided with a cutting knife embodying the invention.

Fig. 2 is a longitudinal sectional elevation, on an enlarged scale, of the standard and throat plate of the machine, showing the knife in the guide slot in said standard.

Fig. 3 is an elevation of a side face of the improved knife.

Fig. 4 is a horizontal section on line 4—4, Fig. 2.

Fig. 5 is a horizontal section of the knife on line 5—5, Fig. 3.

A portion of a reciprocating cloth cutting machine, of the sort to which the improved cutting knife of the present invention is to be applied, is shown in the drawings, Fig. 1, in which 10 is the fixed upright or standard, secured at its lower end to a throat plate 11, which in turn is rigidly attached to the usual base plate 12. The throat plate 11 is provided with a throat or longitudinal recess 13 extending therethrough to the bottom of the base plate, and having a reduced narrow opening 13^a at the top, and the standard 10 is formed with a knife guiding slot 14 extending from the top of the standard to the bottom and ending in the opening 13^a of the throat 13. A motor 15 is fixed to a lateral arm 16 of the standard, said motor being adapted to actuate suitable reciprocating mechanism, including the crank or pitman 17, which is pivotally secured to a slide 18 movable in a vertical guide 19, said slide 18 being rigidly secured to the bifurcated upper end 20 of the cut-

100

105

110

ting knife A by bolts or the like 21, whereby the necessary vertical reciprocating movements are imparted to the knife A.

The knife guide slot 14 is formed with 5 parallel side walls 24 and a rear or back wall 25, adapted to closely engage respectively with side faces 26 and an end or back edge 27 of the knife A, which is further provided with the usual beveled cutting edge 28.

10 In constructions heretofore employed, the back edge 27 of the knife A has been formed so as to extend substantially the full length of the knife and this edge contacted with the back 25 of the guide slot throughout the full 15 length of the knife.

In the present invention the knife is formed so as to remain out of contact with the back of the guide slot for the greater portion of the length of the knife, so as to form 20 a space between these parts into which the accumulations of lint and oil may pass to prevent, or reduce to a minimum, the clogging of the guide slot and consequent interference with the free action of the knife.

25 This is preferably accomplished, as shown in the drawings, by cutting away a portion of the back edge 27 of the knife A, as at 27^a, so as to leave only a relatively short portion of this edge 27, preferably at the bottom, 30 to contact with the back wall 25 of the guide slot 14, and providing a free space or channel 29 in the guide slot 14 behind the knife for the remainder of the length thereof.

In cutting away the back edge of the 35 knife as explained, a shoulder 30 is left between the edges 27, 27^a and this shoulder is preferably made abrupt or square, and in the reciprocating movements of the knife A in the knife guide slot 14, to and from the 40 throat opening 13^a, the lint and other accumulations, as they work into and pass upwardly from the lower end of the slot, will pass into the channel 29 behind the knife, where they will be engaged by the shoulder 30 in the upward movements of said knife 45 and will be gradually pushed upwardly and ejected at the upper end of the guide slot.

The square or abrupt shoulder 30 acts as a 50 scraper to keep the back and side walls of the channel free of accumulations, and makes the knife practically self cleaning.

The described formation of the cutting 55 knife A is such that the efficiency of reciprocating cloth cutting machines provided with the knife is greatly increased, and the machine will operate without clogging of the knife in the guide slot, and, by preventing the deposits from accumulating, reduces the friction and consequent heating to which 60 such knives have heretofore been subjected.

Further, the improved knife can be pro-

duced without any increase in the cost of manufacture.

I claim as my invention:

1. In a cloth cutting machine of the 65 character described, a standard having a knife guiding slot therein, and a reciprocable cutting knife the rear portion of which is shaped to remove the lint and other accumulations from all parts of said guide 70 slot.

2. A cloth cutting machine of the character described, including a standard having a knife guiding slot with parallel side walls and a straight back wall connecting said 75 side walls, and a reciprocable cutting knife having side faces engaging said side walls, and a back edge formed with a relatively short portion adapted to engage said back wall of the slot, said portion being shorter 80 than the cutting edge of said knife, and a relatively longer portion which remains out of contact therewith to provide a channel into which lint and other accumulations may pass to prevent the clogging of said 85 knife in said slot, said knife having a part extending into said channel and adapted to eject said accumulations from said guiding slot.

3. In a cloth cutting machine of the character described including a standard having a knife guiding slot formed with parallel side walls and a straight back wall connecting said side walls, and a reciprocable cutting knife having side faces engaging said 90 side walls, and a back edge formed with a portion adapted to engage said back wall of said slot, and a portion extending lengthwise thereof directly in the rear of the cutting edge of said knife and at a distance 100 from said back wall to form a channel behind said knife into which lint and other accumulations may pass to prevent the clogging of said knife in said slot, and a shoulder formed at the back of said knife adapted to extend across said channel to engage and eject said accumulations from said 105 slot.

4. In a cloth cutting machine, the combination of a knife guiding slot formed with side walls and a back wall, and a reciprocable cutting knife having side faces engaging said side walls and a back edge, said back edge of said knife contacting with a portion only of said back wall, said portion being shorter than the cutting edge of said knife, and the portions of said back wall which are not in contact with the back edge of said knife serving to receive lint and other accumulations without binding 115 said knife in said slot.

GEORGE E. ULRICH.
